(57) **CLAIM**

The ornamental design for a downspout joint, as shown and described.

DESCRIPTION

FIG. 1 is a perspective view of a downspout joint showing my new design;

FIG. 2 is another perspective view thereof;

FIG. 3 is another perspective view thereof;

FIG. 4 is a front view thereof;

FIG. 5 is a back view thereof;

FIG. 6 is a left view thereof;

FIG. 7 is a right view thereof;

FIG. 8 is a top plan view thereof;

FIG. 9 is bottom plan view thereof;

FIG. 10 is a perspective view of the cover opening at the downspout joint; and,

FIG. 11 is a perspective view of the downspout joint shown in a use environment of a downspout.

The broken lines showing a downspout in FIG. 10 illustrate environment only and form no part of the claimed design. All other broken lines illustrate portions of the downspout joint that form no part of the claimed design.

1 Claim, 11 Drawing Sheets
